(74) *Attorney, Agent, or Firm* — Michael Best & Friedrich LLP

(57) **CLAIM**

The ornamental design for a vertical trifold cell phone wallet, as shown and described.

DESCRIPTION

FIG. 1 is a perspective view of a vertical trifold cell phone wallet with an exterior framed pocket and interior slot pockets according to another embodiment showing my new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the vertical trifold cell phone wallet with an exterior framed pocket and interior slot pockets in an open condition;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the vertical trifold cell phone wallet with an exterior framed pocket and interior slot pockets in a stand configuration;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The present application is directed to the design illustrated in the drawings.

The broken line portions of the disclosure are for illustrative purposes only and form no part of the claimed design.

1 Claim, 16 Drawing Sheets
